UNITED STATES PATENT OFFICE.

SAMUEL A. MARKOFF, OF PROVIDENCE, RHODE ISLAND.

MAILING DEVICE.

1,346,502.

Specification of Letters Patent.

Patented July 13, 1920.

Application filed May 9, 1918. Serial No. 233,584.

To all whom it may concern:

Be it known that I, SAMUEL A. MARKOFF, a citizen of the United States, residing at 109 Summer street, city of Providence, in 5 the county of Providence, State of Rhode Island, have invented certain new and useful Improvements in Mailing Devices; and I do hereby declare the following to be a full, clear, and exact description of the invention, such as will enable others skilled 10 in the art to which it appertains to make and use the same.

My invention relates to a writing device, and has for its object the provision of an 15 improved article of this character. More particularly, the aim of the invention is the provision of a compact and convenient article for correspondence or writing, which can be comfortably and conveniently carried on the person, and which can be readily 20 used for writing under all circumstances, and which at the same time is in suitable form for transmission through the mails.

The article of the present invention comprises a mailing device of such shape and 25 configuration as can be conveniently carried about in one's pocket, and which can be conveniently used at times and under circumstances which ordinarily are not 30 suited for writing purposes. Thus, the mailing device embodies a rigid platen having a flat smooth surface adapted to be conveniently held in the palm of the hand, and having wound thereon a relatively long 35 strip of writing material, such as paper. The writing material is adapted to be secured to the platen, for transmission through the mails, by attaching the free outer end of the material to the next adjacent inner layer thereof. The flat, smooth, 40 rigid support and the writing material when wound thereon form a convenient writing pad which can be comfortably held in the palm of the hand and used under any 45 circumstances, as when standing or sitting, or when riding in a car, or the like, or when walking. Furthermore, the platen is so constructed that when the writing material is 50 properly wound thereon and secured thereto, as hereinbefore mentioned, the convolutions of the wound-up writing material cannot be spread apart so as to disclose the writing thereon.

The novel features of my invention which 55 I believe to be patentable are definitely indicated in the appended claim. The con-

struction of the improved mailing device together with its advantages will be better understood from the following description taken in conjunction with the accompanying drawing, in which;

Figure 1 is a plan view of the front or address side of a mailing device embodying the novel features of the present invention and prepared for transmission through the mails;

Fig. 2 is an elevation of the device shown in Fig. 1; and

Fig. 3 is a perspective view showing the manner of holding the device for use in the 70 palm of the hand.

The mailing device comprises a rigid platen 5, preferably made of wood because of its rigidity and of its lightness. The rigidity of this platen is an important feature of the present invention, since it provides a very suitable writing surface, and when held in the palm of the hand, as indicated in Fig. 3 of the accompanying drawings, constitutes a very convenient and satisfactory support for the writing material.

The platen 5 is relatively long and narrow, and is, generally, of such configuration as to adapt it to be conveniently held in the palm of the hand, as indicated in Fig. 3 of 85 the drawings.

The platen is of sufficient thickness to give the desired rigidity hereinbefore referred to. At its four corners the platen is provided with short projecting extensions 90 6, preferably integral with the main portion of the platen. The projecting extensions form suitable guides for the wound-on writing material, and also serve to properly confine the writing material to the support. It will be observed from the foregoing description of the platen, and from the figures of the drawing, that, generally speaking, the platen is of reel-like configuration.

A suitable writing material 7, such as paper or the like, is wound on the platen 5. As many convolutions or layers of the writing material may be wound on the support as desired, and it will be evident that in this 105 manner a relatively long strip of paper can be very conveniently and compactly associated with the platen. The inner end of the writing material may be pasted or otherwise secured to the platen, or may, if desired, be 110 unattached to the platen, since the outer layers of the wound-on writing material

will satisfactorily serve to prevent any slipping of the material with respect to the platen. The free outer end of the writing material is designed to be secured to the next adjacent inner layer of the material by a suitable gummed wafer, such for example, as the postage stamp 8, illustrated in Figs. 1 and 2 of the drawings.

The ends, or edges, of the platen 5, over which the writing material 7 is wound, are preferably beveled or rounded, as indicated at 9 in Fig. 2 of the drawings. This beveling or rounding of the ends of the support is of such a character as to permit the writing material to be drawn tightly about the support without danger of rupturing the material. This rounding or beveling of the ends of the support is of particular advantage, since it insures a close and intimate contact between adjacent layers or convolutions of the writing material, and thus minimizes the opportunity of any unauthorized examination of the writing on the wound-up material when sealed by the gummed wafer 8. The writing material may thus be very closely wound on the reel-like platen 5, and can be securely attached to the support by means of the gummed wafer 8. When thus closely wound and securely attached to the platen, it is extremely difficult to pry apart the convolutions or layers of the wound-up writing material, and thus any unwarranted or unauthorized inspection of the writing is effectively prevented.

The writing device is of very convenient shape and size and can be carried in a vest pocket without inconvenience or discomfort. From the pocket it may be taken out at any time, as when riding in a street car, or walking along the street, and used for jotting down notes or for writing of any nature. The platen, as it is held in the palm of the hand, provides a rigid and satisfactory writing surface, and coöperates with the writing material wound thereon to form a writing pad which can be conveniently used under circumstances which are not normally conducive to writing.

The used or written-upon portions of the writing material can be wound around the hand, preferably by unwinding half a convolution of the material and carrying the platen around the back of the hand and until the opposite supporting side or face is uppermost in the palm of the hand and ready for the writing operation. During the operation of turning the platen and exposing a fresh surface of the writing material, the material already wound on the hand may be slipped about the hand to any extent necessary for again properly positioning the support in the palm of the hand for writing.

The writing device of the present invention is usually prepared for transmission

through the mails, and the outside surface of the free end of the writing material is then provided with suitable printed guides for a postal address, as indicated in Fig. 1 of the drawing. In order to provide sufficient space for the address, the writing material is preferably so wound, or of such length, that its free outer end comes near to the end of the support. The other outside surface of the outer convolution of writing material, being exposed during transmission, may have printed thereon any suitable advertising notice, the address of the sender or the like.

When the entire strip of writing material is used, or when the letter or message is completed, the free end of the writing material is attached to the next adjacent layer of this material by the gummed wafer, as hereinbefore described. The recipient has only to remove or break the seal effected by this gummed wafer in order to be able to unwind the writing material from the platen.

A further particular advantage of the improved mailing device of my present invention is the ease with which it may be employed for jotting down occasionally notes or for writing a letter or message in instalments. Thus the mailing device may be taken from the pocket as occasions for writing present themselves, or as fancy dictates, and may be unwound to the proper place for the next writing instalment. The writing material may then be again wound on the platen and the device replaced in the pocket. It will be observed that the inner convolutions of the writing material are effectively preserved from wear and dirt while the device is carried about between such occasional uses. In this manner the notes or message are maintained in a fresh and unsoiled condition until all of the writing material has been consumed, or until the message is finished. The writing material can then be closely wound on the platen and attached thereto by the gummed wafer for transmission through the mails or until required for further reference.

By making the platen of wood, or similar light material, a satisfactory writing pad is provided upon which the writing material will lie smooth and straight during the writing operation. Both faces of the wooden platen are flat and smooth since both faces are used during the writing operation for supporting the writing material. As previously mentioned, the relatively long narrow configuration of the platen, thus enabling it to be conveniently held in the palm of the hand, and its rigidity are important features of my improved mailing device. Both of these characteristics of the platen, that is, its rigidity and its adaptability to be conveniently held in the palm of the hand, are essential to the device, since only through

them can the device be conveniently and comfortably used under the conditions for which it is intended. On account of these characteristics the device will be found of particular utility to soldiers in service, since it can be employed for writing under conditions which absolutely preclude the use of ordinary writing materials.

I claim:

- 10 A mailing device comprising a light, rigid, flat, oblong platen having a substantially smooth surface and extensions at opposite sides of both ends extending in the direction of the longitudinal axis of said platen, a
- 15 continuous web of writing paper wound upon said platen in the direction of said

longitudinal axis and confined by said extensions, said platen having its opposite end edges rounded in the longitudinal direction to prevent rupture of said paper when 20 wound thereon, the longitudinal edges of said platen being adapted to be grasped in the palm of the hand and thereby supported during the writing operation so that the end of the web is free from interference with 25 the hand, said platen providing a rigid writing surface when so held, and means for securing the free end of said web to the adjacent surface thereof to prevent unwinding of said web. 30

In testimony whereof I affix my signature.

SAMUEL A. MARKOFF.
